ABSTRACT

A pixel circuit of a display panel includes a driving transistor, first to fifth transistors, and a light emitting device. The driving transistor includes a first terminal, a second terminal and a gate terminal. The first transistor is coupled between a power supply terminal and the first terminal of the driving transistor. The second transistor is coupled between the first terminal of the driving transistor and the gate terminal of the driving transistor. The third transistor is coupled between the second terminal of the driving transistor and the gate terminal of the driving transistor. The fourth transistor is coupled between a data input terminal and the second terminal of the driving transistor. The fifth transistor is coupled to the second terminal of the driving transistor. The light emitting device is coupled between the fifth transistor and a reference voltage terminal.

PIXEL CIRCUIT OF DISPLAY PANEL

BACKGROUND OF THE INVENTION

1. Field of the Invention

The present invention relates to a pixel circuit of a display panel, and more particularly, to the structure of a pixel circuit of a display panel capable of canceling the offset of threshold voltages.

2. Description of the Prior Art

Among those next-generation display technologies, the micro organic light emitting diode (micro-OLED) panel has become important in recent years. Unlike conventional LED or OLED panels with their screens being built on a glass substrate, the screen of a micro-OLED panel is directly mounted to a silicon wafer. The silicon-based implementation can achieve a wide variety of benefits such as small size, light weight, low power consumption, high luminous efficiency, high contrast and high pixel density. With the above advantages, the micro-OLED panel is particularly suitable for augmented reality (AR) and virtual reality (VR) applications.

Similar to the conventional OLED panels, the micro-OLED panels also suffer from uneven brightness between display pixels that is caused by mismatch of driving transistors and/or OLEDs, which is called the Mura effect. People in the industry are making efforts to propose various pixel structures to improve the unevenness problem and solve the Mura effect for the display panels.

SUMMARY OF THE INVENTION

It is therefore an objective of the present invention to provide a novel pixel circuit for an organic light emitting diode (OLED) panel, especially a micro-OLED panel, so as to solve the abovementioned problems.

An embodiment of the present invention discloses a pixel circuit of a display panel. The pixel circuit comprises a driving transistor, a first transistor, a second transistor, a third transistor, a fourth transistor, a fifth transistor and a light emitting device. The driving transistor comprises a first terminal, a second terminal and a gate terminal. The first transistor comprises a first terminal and a second terminal, where the first terminal is coupled to a power supply terminal, and the second terminal is coupled to the first terminal of the driving transistor. The second transistor comprises a first terminal and a second terminal, where the first terminal is coupled to the first terminal of the driving transistor, and the second terminal is coupled to the gate terminal of the driving transistor. The third transistor comprises a first terminal and a second terminal, where the first terminal is coupled to the second terminal of the driving transistor, and the second terminal is coupled to the gate terminal of the driving transistor. The fourth transistor comprises a first terminal and a second terminal, where the first terminal is coupled to a data input terminal of the pixel circuit, and the second terminal is coupled to the second terminal of the driving transistor. The fifth transistor comprises a first terminal and a second terminal, where the first terminal is coupled to the second terminal of the driving transistor. The light emitting device comprises a first terminal and a second terminal, where the first terminal is coupled to the second terminal of the fifth transistor, and the second terminal is coupled to a reference voltage terminal to receive ground or negative voltage.

2

to the second terminal of the fifth transistor, and the second terminal is coupled to a reference voltage terminal to receive ground or negative voltage.

Another embodiment of the present invention discloses a pixel circuit of a display panel. The pixel circuit comprises a driving transistor, a first transistor, a second transistor, a third transistor, a fourth transistor, a fifth transistor, a light emitting device and a first capacitor. The driving transistor comprises a first terminal, a second terminal and a gate terminal. The first transistor comprises a first terminal and a second terminal, where the first terminal is coupled to a power supply terminal, and the second terminal is coupled to the first terminal of the driving transistor. The second transistor comprises a first terminal and a second terminal, where the first terminal is coupled to the first terminal of the driving transistor, and the second terminal is coupled to the gate terminal of the driving transistor. The third transistor comprises a first terminal and a second terminal, where the first terminal is coupled to the second terminal of the driving transistor, and the second terminal is coupled to the gate terminal of the driving transistor. The fourth transistor comprises a first terminal and a second terminal, where the first terminal is coupled to a data input terminal of the pixel circuit, and the second terminal is coupled to the first terminal of the driving transistor. The fifth transistor comprises a first terminal and a second terminal, where the first terminal is coupled to the second terminal of the driving transistor. The light emitting device comprises a first terminal and a second terminal, where the first terminal is coupled to the second terminal of the fifth transistor, and the second terminal is coupled to a reference voltage terminal to receive ground or negative voltage. The first capacitor comprises a first terminal and a second terminal, where the first terminal is coupled to the gate terminal of the driving transistor, and the second terminal is coupled to the first terminal of the driving transistor.

These and other objectives of the present invention will no doubt become obvious to those of ordinary skill in the art after reading the following detailed description of the preferred embodiment that is illustrated in the various figures and drawings.

BRIEF DESCRIPTION OF THE DRAWINGS

FIG. 1 is a schematic diagram of a pixel circuit of a display panel.

FIGS. 2A, 2B and 2C are schematic diagrams of a pixel circuit of a display panel according to an embodiment of the present invention.

FIGS. 3A, 3B and 3C are schematic diagrams of a pixel circuit of a display panel according to an embodiment of the present invention.

FIGS. 4A, 4B and 4C are schematic diagrams of a pixel circuit of a display panel according to an embodiment of the present invention.

FIGS. 5A, 5B and 5C are schematic diagrams of another pixel circuit of a display panel according to an embodiment of the present invention.

DETAILED DESCRIPTION

FIG. 1 is a schematic diagram of a pixel circuit 10 of a display panel. The display panel may be an organic light emitting diode (OLED) panel or a micro-OLED panel. The pixel circuit 10 includes a driving transistor MDRV, a data enable transistor MDEN, an emission control transistor MEM, a storage capacitor C1 and an OLED L1. The driving

transistor MDRV is configured to control the OLED L1 to emit light. The data enable transistor MDEN may serve as a switch for receiving an input data Vdata. The input data Vdata that arrives at the gate terminal of the driving transistor MDRV may determine the current magnitude flowing through the OLED L1, thereby determining the brightness of the OLED L1. The emission control transistor MEM may serve as a switch for controlling the emission of the OLED L1.

The pixel circuit 10 may be operated by receiving a power supply voltage VDD, a data enable signal T_DEN and an emission control signal T_EM. More specifically, the data enable transistor MDEN is controlled by the data enable signal T_DEN, and the emission control transistor MEM is controlled by the emission control signal T_EM.

The operations of the pixel circuit 10 include two phases: a scan phase and an emission phase. In the scan phase, the data enable transistor MDEN is turned on and the emission control transistor MEM is turned off. The input data Vdata may be forwarded to the gate terminal of the driving transistor MDRV and stored in the storage capacitor C1. In the emission phase following the scan phase, the emission control transistor MEM is turned on. A driving current I_{drv1} , which is generated by the driving transistor MDRV based on the input data Vdata, may flow through the OLED L1 to determine the brightness emitted by the OLED L1.

In the driving transistor MDRV, the magnitude of the driving current I_{drv1} may be determined based on the correspondence of the driving current I_{drv1} and the source-to-gate voltage Vsg of the driving transistor MDRV. Based on the mobility of the driving transistor MDRV, the relationship of the driving current I_{drv1} and the source-to-gate voltage Vsg may follow a square law or exponential law. For example, if the pixel circuit 10 is implemented with a thin-film transistor (TFT) process, the mobility is lower and the driving current I_{drv1} output by the driving transistor MDRV may be relatively low, and it is more possible that the driving transistor MDRV operates in the saturation region to follow the square law. If the pixel circuit 10 is implemented with a complementary metal-oxide semiconductor (CMOS) process as the silicon-based implementation of the micro-OLED panel, the mobility is higher than in the TFT process. Therefore, in order to achieve identical current magnitudes, the driving transistor MDRV may operate in the sub-threshold region to follow the exponential law.

No matter whether the driving transistor MDRV operates based on the square law or exponential law, the driving current I_{drv1} and the source-to-gate voltage Vsg have one-to-one correspondence, so that the driving current I_{drv1} may be determined according to the source-to-gate voltage Vsg, which is further determined according to the input data Vdata. For the sake of brevity, the formula of square law is described hereinafter, as shown below:

$$I_{drv1} = \frac{1}{2} \beta [Vsg - Vthp]^2 \quad (1)$$

where β represents the gain factor of the driving transistor MDRV, and is determined according to the mobility, normalized oxide capacitance, and width/length ratio of the transistor; and Vthp is the threshold voltage of the driving transistor MDRV. Since the source voltage of the driving transistor MDRV equals the power supply voltage VDD and the gate voltage of the driving transistor MDRV equals the input data Vdata, Equation (1) may be rewritten as:

$$I_{drv1} = \frac{1}{2} \beta [VDD - Vdata - Vthp]^2 \quad (2)$$

Note that the threshold voltage Vthp is included in the formula for calculating the driving current I_{drv1} . In the display panel, the threshold voltage Vthp of different pixels may not be uniform due to process and/or device variations. The mismatch and offset of the threshold voltage Vthp may generate uneven brightness between the pixels, thereby generating the Mura effect. Therefore, the present invention provides a novel pixel circuit with appropriate controls to let the Mura effect caused by the offsets of the threshold voltage Vthp to be minimized.

FIGS. 2A-2C are schematic diagrams of a pixel circuit 20 of a display panel according to an embodiment of the present invention. The pixel circuit 20 includes a driving transistor MDRV, 5 control transistors M1-M5, a storage capacitor C2 and a light emitting device L2, to realize a 6T1C structure. The driving transistor MDRV is configured to control the light emitting device L2 to emit light; that is, the driving transistor MDRV may generate a driving current I_{drv2} according to the received input data Vdata, and output the driving current I_{drv2} to drive the light emitting device L2 to emit light. The storage capacitor C2, which may be coupled between the gate terminal of the driving transistor MDRV and a power supply terminal that supplies the power supply voltage VDD, is configured to store the input data Vdata forwarded to the gate terminal of the driving transistor MDRV, as similar to the storage capacitor C1 of the pixel circuit 10.

The control transistors M1-M5 may be deployed and controlled appropriately to cancel the influence of the threshold voltage Vthp of the driving transistor MDRV on the driving current I_{drv2} . In detail, the control transistor M1 is coupled to the upper terminal of the driving transistor MDRV, where the source terminal of the control transistor M1 may be coupled to a power supply terminal to receive the power supply voltage VDD, the drain terminal of the control transistor M1 may be coupled to the upper terminal of the driving transistor MDRV, and the gate terminal of the control transistor M1 may receive an emission control signal T_EM2. The control transistor M1 may serve as a switch for controlling the pixel circuit 20 to receive the power supply voltage VDD.

The control transistor M2 is coupled between the upper terminal and the gate terminal of the driving transistor MDRV, to serve as a switch for initialization and data reception. In detail, a first terminal of the control transistor M2 may be coupled to the upper terminal of the driving transistor MDRV, a second terminal of the control transistor M2 may be coupled to the gate terminal of the driving transistor MDRV, and the gate terminal of the control transistor M2 may receive an offset control signal T_AZ. The control transistor M2 may be used to conduct the gate terminal and the upper terminal of the driving transistor MDRV, to form a diode-connected structure when the input data Vdata is received, so as to obtain the information of the threshold voltage Vthp at the gate terminal of the driving transistor MDRV.

The control transistor M3 is coupled between the lower terminal and the gate terminal of the driving transistor MDRV, to serve as a switch for initialization. In detail, a first terminal of the control transistor M3 may be coupled to the lower terminal of the driving transistor MDRV, a second terminal of the control transistor M3 may be coupled to the gate terminal of the driving transistor MDRV, and the gate terminal of the control transistor M3 may receive an initialization control signal T_INI. The control transistor M3 may be used to initialize the driving transistor MDRV to a lower

voltage in each operation cycle, allowing the input data V_{data} to be successfully received by the driving transistor MDRV after initialization.

The control transistor M4 is coupled to the lower terminal of the driving transistor MDRV, to serve as a switch for controlling display data reception. In detail, a first terminal of the control transistor M4 may be coupled to a data input terminal of the pixel circuit 20 for receiving the input data V_{data} , a second terminal of the control transistor M4 may be coupled to the lower terminal of the driving transistor MDRV, and the gate terminal of the control transistor M4 may receive a data enable signal T_DEN. The control transistor M4 may be used to control the pixel circuit 20 to receive the input data V_{data} .

The control transistor M5 is coupled between the lower terminal of the driving transistor MDRV and the light emitting device L2, to serve as a switch for controlling light emission of the pixel circuit 20. In detail, a first terminal of the control transistor M5 may be coupled to the lower terminal of the driving transistor MDRV, a second terminal of the control transistor M5 may be coupled to the light emitting device L2, and the gate terminal of the control transistor M5 may receive an emission control signal T_EM1. The control transistor M5 may be used to control the currents generated by the driving transistor MDRV to flow to the light emitting device L2.

The light emitting device L2 includes a first terminal coupled to the control transistor M5 and a second terminal coupled to a reference voltage terminal to receive ground or negative voltage. The light emitting device L2, which is configured to emit light as being driven by the driving current I_{drv2} received from the driving transistor MDRV, may be any device capable of emitting light by receiving currents, such as an OLED.

The operations of the pixel circuit 20 include three phases: a precharge phase, a scan phase and an emission phase. FIGS. 2A-2C illustrate the circuit structures and related waveforms of the control signals in the pixel circuit 20, where FIG. 2A shows the operations of the precharge phase, FIG. 2B shows the operations of the scan phase, and FIG. 2C shows the operations of the emission phase. Note that in the pixel circuit 20, the driving transistor MDRV and the control transistors M1-M5 are all PMOS transistors, and thus the signals in low level may turn on the corresponding transistors and in high level may turn off the corresponding transistors.

As shown in FIG. 2A, in the precharge phase (also called initial phase), the control transistors M2, M3, M4 and M5 are turned on, and the control transistor M1 is turned off. An initial voltage V_{ini} may be received from the data input terminal. Since the control transistors M2, M3 and M4 are all turned on, the source, gate and drain terminals of the driving transistor MDRV are initialized or reset to the initial voltage V_{ini} . Since the control transistor M5 is turned on, the anode of the light emitting device L2 is also initialized or reset to the initial voltage V_{ini} . The control transistor M1 is turned off to prevent a current conducting path through the driving transistor MDRV and the light emitting device L2 to generate unnecessary current consumption.

In the precharge phase, the light emitting device L2 should not emit light; hence, the value of the initial voltage V_{ini} should be low enough to control the current flowing through the light emitting device L2 to be lower than a specific threshold so that the light emitting device L2 is prevented from emitting unwanted light. The value of the initial voltage V_{ini} received by the driving transistor MDRV should also be low enough to ensure that the input data

V_{data} can be successfully input to the driving transistor MDRV in the next phase. Otherwise, if the level of the initial voltage V_{ini} is excessively high, the initial voltage V_{ini} at the gate terminal of the driving transistor MDRV may turn off the driving transistor MDRV. For example, the initial voltage V_{ini} should be smaller than the minimal data voltage with a difference greater than the threshold voltage V_{thp} , i.e., to satisfy $V_{data}-V_{ini} > V_{thp}$. In an embodiment, the minimal input data V_{data} may be 4V, and the initial voltage V_{ini} may be equal to 2V to achieve the purposes of turning on the driving transistor MDRV and turning off the light emitting device L2.

As shown in FIG. 2B, in the scan phase, the control transistors M2 and M4 are turned on, and the control transistors M1, M3 and M5 are turned off. The input data V_{data} may be received from the data input terminal. In this embodiment, the pixel circuit 20 may receive the initial voltage V_{ini} from the data input terminal in the precharge phase, and receive the input data V_{data} from the data input terminal in the scan phase. In other words, the initial voltage V_{ini} and the input data V_{data} are received from the same terminal, so that the deployment of signal/data lines on the display panel may be simplified.

In the scan phase, the driving transistor MDRV receives the input data V_{data} through the control transistor M4, and the gate terminal of the driving transistor MDRV starts to be charged. At this moment, the lower terminal of the MDRV may be regarded as the source terminal, which receives the input data V_{data} to generate the gate voltage $V_{data}-V_{thp'}$ with the source-to-gate voltage V_{sg} of the driving transistor MDRV equal to $V_{thp'}$, where $V_{thp'}$ is the threshold voltage of the driving transistor MDRV in consideration of body effect (slightly different from the intrinsic threshold voltage V_{thp} without body effect). The charges corresponding to the gate voltage $V_{data}-V_{thp'}$ will be stored in the storage capacitor C2. Since the control transistor M2 is turned on, the upper terminal (which may be regarded as the drain terminal in this phase) of the driving transistor MDRV may also be charged to the voltage $V_{data}-V_{thp'}$. After the gate voltage of the driving transistor MDRV reaches $V_{data}-V_{thp'}$, the driving transistor MDRV may become cutoff and stop charging at the end of the scan phase.

As mentioned above, the driving transistor MDRV is initialized or reset to the initial voltage V_{ini} in the precharge phase prior to the scan phase. At the start of the scan phase, the initial voltage V_{ini} is low enough to ensure that the driving transistor MDRV is turned on when the input data V_{data} arrives.

In the scan phase, the control transistor M2 is turned on by the offset control signal T_AZ, and thus the control transistor M2 and the driving transistor MDRV may form a diode-connected structure. The diode-connected structure allows the driving transistor MDRV to generate the gate voltage $V_{data}-V_{thp'}$ containing the information of the threshold voltage $V_{thp'}$, which may be stored in the storage capacitor C2 at the end of the scan phase.

As shown in FIG. 2C, in the emission phase, the control transistors M1 and M5 are turned on, and the control transistors M2, M3 and M4 are turned off. The turn-on control transistor M1 may charge the upper terminal of the driving transistor MDRV to the power supply voltage VDD. In this phase, the upper terminal of the driving transistor MDRV may be regarded as the source terminal of the driving transistor MDRV since this upper terminal receives the power supply voltage VDD which may be higher than the voltage at the lower terminal of the driving transistor MDRV. The voltage at the lower terminal of the driving transistor

MDRV is equal to the anode voltage of the light emitting device **L2**, V_{EM} , which is a voltage generated by the light emitting device **L2** under the driving current I_{DRV2} .

At this moment, the source-to-gate voltage V_{sg} of the driving transistor MDRV may be equal to $VDD - (V_{data} - V_{thp}')$, which is used to determine the magnitude of the driving current I_{drv2} to be used for driving the light emitting device **L2**. The control transistor **M5** is also turned on to pass the driving current I_{drv2} to the light emitting device **L2**, allowing the light emitting device **L2** to emit light. Similarly, the operations of the driving transistor MDRV in the pixel circuit **20** may follow the square law or exponential law based on the implementations and corresponding device mobility. Taking the square law as an example, the driving current I_{drv2} may be calculated as follows:

$$I_{drv2} = \frac{1}{2} \beta [V_{sg} - V_{thp}]^2; \quad (3)$$

$$I_{drv2} = \frac{1}{2} \beta [VDD - (V_{data} - V_{thp}') - V_{thp}]^2; \quad (4)$$

where the definition of the parameter B is identical to that described in Equation (1), and will not be repeated herein.

Since the threshold voltage V_{thp}' includes the body effect where the drain voltage of the driving transistor MDRV is equal to V_{data} , Equation (4) may be rewritten as:

$$I_{drv2} = \frac{1}{2} \beta [VDD - (V_{data} - (V_{thp} + \gamma(\sqrt{2\Phi F} + VDD - V_{data}) - \sqrt{2\Phi F})) - V_{thp}]^2. \quad (5)$$

In Equation (5), the threshold voltage V_{thp} may be canceled out to become:

$$I_{drv2} = \frac{1}{2} \beta [VDD - V_{data} + \gamma(\sqrt{2\Phi F} + VDD - V_{data} - \sqrt{2\Phi F})]^2; \quad (6)$$

where γ is the body effect parameter, and $2\Phi F$ is the surface potential.

As can be seen, the formula for calculating the driving current I_{drv2} only includes a signal dependent term consisting of the input data V_{data} , and will not depend on the threshold voltage V_{thp} , which means that the offset of the threshold voltage V_{thp} between pixels will not influence the current magnitude and the brightness of the light emitting device **L2**. Other parameters such as β or γ may not generate significant mismatch or offset that needs to be canceled. As a result, the problem of brightness non-uniformity may be solved.

During the operations of the pixel circuit **20**, the control transistors **M1-M5** are controlled by the initialization control signal T_{INI} , the data enable signal T_{DEN} , the offset control signal T_{AZ} , and the emission control signals T_{EM1} and T_{EM2} . Note that the waveforms of these signals shown in FIGS. 2A-2C are merely an example for illustrating a method of handling the operations by allocating the turn-on time and turn-off time of several control signals. For example, at the start of the emission phase, the data enable signal T_{DEN} turns off the control transistor **M4**

slightly earlier than the offset control signal T_{AZ} turns off the control transistor **M2**, as shown in FIGS. 2A-2C. Alternatively, the data enable signal T_{DEN} and the offset control signal T_{AZ} may toggle simultaneously, or the offset control signal T_{AZ} may toggle earlier. In another embodiment, the control transistors **M2** and **M4** may be controlled by the same control signal. In addition, at the start of the emission phase, the emission control signal T_{EM2} turns on the control transistor **M1** slightly earlier than the emission control signal T_{EM1} turns on the control transistor **M5**, as shown in FIGS. 2A-2C. In another embodiment, these control signals' toggling order may also be modified.

Also note that the structure of the pixel circuit **20** shown in FIGS. 2A-2C is merely an example, and may be modified or adjusted to improve the performance. FIGS. 3A-3C are schematic diagrams of a pixel circuit **30** of a display panel according to an embodiment of the present invention. The structure of the pixel circuit **30** is similar to the structure of the pixel circuit **20**, so signals and elements having similar functions are denoted by the same symbols. The difference between the pixel circuit **30** and the pixel circuit **20** is that, the pixel circuit **30** further includes a coupling capacitor **C3**, which is coupled to the anode of the light emitting device **L2**. Similarly, FIGS. 3A-3C illustrate the circuit structures and related waveforms of the control signals in the pixel circuit **30** for the precharge phase, the scan phase and the emission phase, respectively, and the operations are similar to those illustrated in FIGS. 2A-2C.

In this embodiment, the control transistor **M5** is turned off in the precharge phase. Therefore, the initial voltage V_{ini} is only used to initialize the driving transistor MDRV, while the light emitting device **L2** is initialized or reset through the coupling capacitor **C3**. The coupling capacitor **C3** may couple an emission off signal $T_{EM1'}$ to the anode of the light emitting device **L2** to perform initialization. At the start of the precharge phase, the emission off signal $T_{EM1'}$ has a falling voltage ΔV , which is coupled to the anode of the light emitting device **L2** to prevent the light emitting device **L2** from emitting light in the precharge phase (and also in the scan phase). In an embodiment, the emission off signal $T_{EM1'}$ may be an inverse signal of the emission control signal T_{EM1} that controls the control transistor **M5**.

In the pixel circuit **20**, the light emitting device **L2** is initialized by using the initial voltage V_{ini} . The initial voltage V_{ini} is forwarded through PMOS switches, and may not be easily forwarded if the value of the initial voltage V_{ini} approaches 0V. In contrast, in the pixel circuit **30**, the light emitting device **L2** is initialized by coupling the falling voltage ΔV to its anode, allowing the anode voltage to decrease to an extremely low level, even lower than 0V. This ensures that the light emitting device **L2** will not emit unwanted light in the precharge phase and the scan phase.

As mentioned above, the pixel circuit of the present invention is applicable to a micro-OLED panel, which is implemented with the CMOS process having a higher mobility; hence, a general current operation range of the light emitting diode (e.g., between 10 pA and 5 nA) may be generated by using small data voltages, which are within an input voltage range of 200 mV. This input voltage range is quite small and cannot be easily implemented to generate a desired gamma curve.

In order to increase the input voltage range, an improvement of the pixel circuit **20** may be applied. Please refer to FIGS. 4A-4C, which are schematic diagrams of a pixel circuit **40** of a display panel according to an embodiment of the present invention. The structure of the pixel circuit **40** is similar to the structure of the pixel circuit **20**, so signals and

elements having similar functions are denoted by the same symbols. The difference between the pixel circuit **40** and the pixel circuit **20** is that, the pixel circuit **40** further includes control transistors **M6** and **M7** and a capacitor **C4** coupled to the gate terminal of the driving transistor MDRV. Similarly, FIGS. **4A-4C** illustrate the circuit structures and related waveforms of the control signals in the pixel circuit **40** for the precharge phase, the scan phase and the emission phase, respectively, and the operations are similar to those illustrated in FIGS. **2A-2C**.

In this embodiment, a first terminal of the capacitor **C4** is coupled to the gate terminal of the driving transistor MDRV, and a second terminal of the capacitor **C4** is coupled to the control transistors **M6** and **M7**. The control transistor **M6** may serve as a switch for receiving a positive reference voltage **Vref**, where a first terminal of the control transistor **M6** may be coupled to the capacitor **C4**, a second terminal of the control transistor **M6** may be coupled to a positive reference voltage terminal for receiving the positive reference voltage **Vref**, and the gate terminal of the control transistor **M6** may receive the emission control signal **T_EM1**. The positive reference voltage **Vref** may be any appropriate positive voltage. In an embodiment, the positive reference voltage **Vref** is equal to or less than the power supply voltage **VDD**. The control transistor **M7** may serve as a switch for receiving the input data **Vdata**, where a first terminal of the control transistor **M7** may be coupled to the capacitor **C4**, a second terminal of the control transistor **M7** may be coupled to the data input terminal for receiving the input data **Vdata**, and the gate terminal of the control transistor **M7** may receive a sampling control signal **T_SMP**.

Another capacitor **C5**, which is further illustrated in the pixel circuit **40**, may be an actually deployed capacitor or parasitic capacitor. If the capacitor **C5** is actually deployed, it may be coupled between the gate terminal of the driving transistor MDRV and a power supply terminal for receiving the power supply voltage **VDD**, as shown in FIGS. **4A-4C**.

The control method of the pixel circuit **40** is similar to the control method of the pixel circuit **20**, except that the pixel circuit **40** receives an additional sampling control signal **T_SMP**, which may turn on the control transistor **M7** in the scan phase and turn off the control transistor **M7** in the precharge phase and the emission phase.

In the scan phase, the control transistor **M7** is turned on and the control transistor **M6** is turned off, and the second terminal of the capacitor **C4** receives the input data **Vdata** through the control transistor **M7**. Meanwhile, the first terminal of the capacitor **C4** receives the gate voltage of the driving transistor MDRV which is equal to **Vdata**-**Vthp'**, and thus the information of the threshold voltage **Vthp'** is stored. Subsequently, in the emission phase, the control transistor **M6** is turned on and the control transistor **M7** is turned off, and the second terminal of the capacitor **C4** receives the positive reference voltage **Vref**. The voltage difference **Vref**-**Vdata** at the second terminal of the capacitor **C4** is coupled to its first terminal, to move the gate voltage of the driving transistor MDRV to

$$Vdata - Vthp' + \frac{C4}{C4 + C5} (Vref - Vdata).$$

In a similar manner, the driving current I_{drv3} for driving the light emitting device **L2** of the pixel circuit **40** in the

emission phase may be calculated based on the source-to-gate voltage **Vsg** of the driving transistor MDRV, which is expressed as:

$$I_{drv3} = \frac{1}{2} \beta [VDD - Vdata + \gamma(\sqrt{2\Phi F + VDD - Vdata} - \sqrt{2\Phi F}) - \frac{C4}{C4 + C5} (Vref - Vdata)]^2; \quad (7)$$

10

where the threshold voltage **Vthp** is perfectly canceled. Equation (7) may further be rearranged as:

$$I_{drv3} = \frac{1}{2} \beta [VDD - \frac{C5}{C4 + C5} Vdata + \gamma(\sqrt{2\Phi F + VDD - Vdata} - \sqrt{2\Phi F}) - \frac{C4}{C4 + C5} Vref]^2. \quad (8)$$

20

In an embodiment, the positive reference voltage **Vref** may be equal to the power supply voltage **VDD**, and thus Equation (8) may further be simplified as:

$$I_{drv3} = \frac{1}{2} \beta \left[\frac{C5}{C4 + C5} (VDD - Vdata) + \gamma(\sqrt{2\Phi F + VDD - Vdata} - \sqrt{2\Phi F}) \right]^2. \quad (9)$$

30

As can be seen in Equation (8) or (9), the factor of the input data **Vdata** is divided by a ratio **C5/(C4+C5)**, which means that the same current range may be generated by a larger input data range. It should be noted that the input data range becomes larger if the value of the capacitor **C5** is smaller; hence, it is preferable to take the parasitic capacitor at the gate terminal of the driving transistor MDRV to realize the capacitor **C5**.

As a result, based on the structure of the pixel circuit **40**, a larger variation of the input data **Vdata** may be applied to generate a target current range for driving the light emitting device **L2**, thereby increasing the input data range. The increased input data range facilitates the settings of the gamma curve, so as to realize a satisfactory visual effect.

Please refer to FIGS. **5A-5C**, which are schematic diagrams of another pixel circuit **50** of a display panel according to an embodiment of the present invention. The structure of the pixel circuit **50** is similar to the structure of the pixel circuit **40**, so signals and elements having similar functions are denoted by the same symbols. The difference between the pixel circuit **50** and the pixel circuit **40** is that, in the pixel circuit **50**, the control transistor **M4** for receiving the initial voltage **Vini** and the input data **Vdata** is coupled to the upper terminal of the driving transistor MDRV. Correspondingly, the control transistor **M2**, which is coupled between the upper terminal (which may be the source terminal) and the gate terminal of the driving transistor MDRV, is controlled by the initialization control signal **T_INI**, and the control transistor **M3**, which is coupled between the lower terminal (which may be the drain terminal) and the gate terminal of the driving transistor MDRV, is controlled by the offset control signal **T_AZ**. That is, the roles played by the control transistor **M2** and the control transistor **M3** are exchanged. In such a situation, in the scan phase, the control transistor **M3** is conducted with the driving transistor MDRV to form the diode-connected structure, while the control transistor **M2** is off.

11

Similarly, the capacitors C4 and C5 are used for dividing the voltage of the input data Vdata to increase the input voltage range. In this embodiment, the capacitor C4 is coupled between the upper terminal and the gate terminal of the driving transistor MDRV, and the capacitor C5 is coupled between the gate terminal of the driving transistor MDRV and a power supply terminal that supplies the power supply voltage VDD. The capacitor C5 may be an actually deployed capacitor or parasitic capacitor. In the pixel circuit 50, the formula for calculating the driving current I_{DRV3} for driving the light emitting device L2 may also be referred to Equation (8) or (9). The structure of the pixel circuit 50 may achieve the effect of increasing the input voltage range by using only 6 transistors, which may be simpler and more cost-saving than the 8-transistor structure of the pixel circuit 40.

Similarly, the waveforms of the control signals in the pixel circuit 50 for the precharge phase, the scan phase and the emission phase are shown in FIGS. 5A-5C, respectively. Other operations of the pixel circuit 50 are similar to those described in the above paragraphs, and will not be repeated herein.

Please note that the present invention aims at providing a novel pixel circuit for canceling the offset generated from the threshold voltage of the driving transistor. Those skilled in the art may make modifications and alterations accordingly. For example, in the above embodiments, the transistors in the pixel circuit are PMOS transistors; but in other embodiments, similar implementations may be realized by using NMOS transistors, where the control signals and the initial voltage may be modified accordingly. In addition, the driving transistor may be operated in the saturation region to follow the abovementioned equations, or in the sub-threshold region or linear region to follow another formula based on the exponential law, depending on the application of the display panel. The threshold voltage may be canceled in a similar manner when the exponential law is applied. Further, the pixel circuit of the present invention may be applied to any self-luminous panel, which includes, but not limited to, an OLED panel, mini-LED panel, micro-LED panel, and micro-OLED panel.

To sum up, the present invention provides a pixel circuit for canceling the offset generated from the threshold voltage of the driving transistor. In the scan phase, the driving transistor may receive the input data through a lower terminal that is coupled to the light emitting device, and the input data with information of the threshold voltage are received at the gate terminal of the driving transistor and stored in the storage capacitor, and then canceled in the emission phase. In an embodiment, the light emitting device may be initialized by using a coupling capacitor, which couples a falling voltage to prevent the light emitting device from emitting unwanted light in the precharge phase and the scan phase. In an embodiment, a capacitor is coupled between the data input terminal and the gate terminal of the driving transistor, to divide the input data by a ratio when the input data is applied to generate the driving current in the emission phase, so as to increase the input voltage range. In another embodiment, the driving transistor may receive the input data through an upper terminal, i.e., the source terminal, with a capacitor coupled between the upper terminal and the gate terminal of the driving transistor, so as to achieve the effect of increasing the input voltage range with a fewer number of transistors and simpler circuit structure.

Those skilled in the art will readily observe that numerous modifications and alterations of the device and method may be made while retaining the teachings of the invention.

12

Accordingly, the above disclosure should be construed as limited only by the metes and bounds of the appended claims.

What is claimed is:

1. A pixel circuit of a display panel, comprising:
  - a driving transistor, comprising a first terminal, a second terminal and a gate terminal;
  - a first transistor, comprising:
    - a first terminal, coupled to a power supply terminal; and
    - a second terminal, coupled to the first terminal of the driving transistor;
  - a second transistor, comprising:
    - a first terminal, coupled to the first terminal of the driving transistor; and
    - a second terminal, coupled to the gate terminal of the driving transistor;
  - a third transistor, comprising:
    - a first terminal, coupled to the second terminal of the driving transistor; and
    - a second terminal, coupled to the gate terminal of the driving transistor;
  - a fourth transistor, comprising:
    - a first terminal, coupled to a data input terminal of the pixel circuit; and
    - a second terminal, coupled to the second terminal of the driving transistor;
  - a fifth transistor, comprising:
    - a first terminal, coupled to the second terminal of the driving transistor; and
    - a second terminal;
  - a light emitting device, comprising:
    - a first terminal, coupled to the second terminal of the fifth transistor; and
    - a second terminal, coupled to a reference voltage terminal;
  - a first capacitor, comprising:
    - a first terminal, coupled to the gate terminal of the driving transistor; and
    - a second terminal;
  - a sixth transistor, comprising:
    - a first terminal, coupled to the second terminal of the first capacitor; and
    - a second terminal; and
  - a seventh transistor, comprising:
    - a first terminal, coupled to the second terminal of the first capacitor; and
    - a second terminal, coupled to the data input terminal.
2. The pixel circuit of claim 1, further comprising:
  - a capacitor, coupled between the gate terminal of the driving transistor and the power supply terminal.
3. The pixel circuit of claim 1, wherein the pixel circuit is configured to receive an initial voltage from the data input terminal in a precharge phase, and receive an input data from the data input terminal in a scan phase.
4. The pixel circuit of claim 1, wherein the second transistor and the driving transistor form a diode-connected structure in a scan phase.
5. The pixel circuit of claim 1, wherein the second transistor and the third transistor are turned on to initialize the driving transistor in a precharge phase.
6. The pixel circuit of claim 1, wherein the first transistor and the fifth transistor are turned on to pass a current to the light emitting device in an emission phase.
7. The pixel circuit of claim 1, further comprising:
  - a capacitor, coupled to the first terminal of the light emitting device, configured to couple an emission off signal to the light emitting device.

13

8. The pixel circuit of claim 1, further comprising:
 a second capacitor, comprising:
 a first terminal, coupled to the gate terminal of the
 driving transistor; and
 a second terminal, coupled to the power supply terminal. 5
9. A pixel circuit of a display panel, comprising:
 a driving transistor, comprising a first terminal, a second terminal and a gate terminal;
 a first transistor, comprising:
 a first terminal, coupled to a power supply terminal; and
 a second terminal, coupled to the first terminal of the
 driving transistor; 10
 a second transistor, comprising:
 a first terminal, coupled to the first terminal of the
 driving transistor; and
 a second terminal, coupled to the gate terminal of the
 driving transistor; 15
 a third transistor, comprising:
 a first terminal, coupled to the second terminal of the
 driving transistor; and 20

14

- a second terminal, coupled to the gate terminal of the
 driving transistor;
 a fourth transistor, comprising:
 a first terminal, coupled to a data input terminal of the
 pixel circuit; and
 a second terminal, directly connected to the first terminal
 of the driving transistor;
 a fifth transistor, comprising:
 a first terminal, coupled to the second terminal of the
 driving transistor; and
 a second terminal;
 a light emitting device, comprising:
 a first terminal, coupled to the second terminal of the
 fifth transistor; and
 a second terminal, coupled to a reference voltage
 terminal; and
 a first capacitor, comprising:
 a first terminal, coupled to the gate terminal of the
 driving transistor; and
 a second terminal, coupled to the first terminal of the
 driving transistor.
